UNITED STATES PATENT OFFICE.

MORRIS COHEN, OF BROOKLYN, NEW YORK.

BAG-FRAME.

1,114,449.

Specification of Letters Patent. Patented Oct. 20, 1914.

Application filed October 22, 1913. Serial No. 796,566.

To all whom it may concern:

Be it known that I, MORRIS COHEN, a subject of the Czar of Russia, residing at Brooklyn, in the county of Kings and State 5 of New York, have invented certain new and useful Improvements in Bag-Frames; and I do hereby declare the following to be a full, clear, and exact description of the invention, such as will enable others skilled in the art 10 to which it appertains to make and use the same, reference being had to the accompanying drawings, and to characters of reference marked thereon, which form a part of this specification.

15 The present invention relates, generally, to improvements in bag-frames; and, this invention has reference, more particularly, to a novel construction of hingeless bag-frame for hand-bags, satchels, traveling- 20 bags, shopping-bags and the like.

The invention has for its principal object to provide a simple, strong and durable hingeless bag-frame provided with means for strengthening the frame-members and 25 assuring their proper coöperation and association when the said frame-members are brought into their closed relation, the said frame-members being so associated, when closed, as to prevent the frame-members 30 from sagging away from each other at their free ends, or becoming bent or misshapened.

Another object of the present invention is to provide a construction of hingeless bag-frame which may serve to suspend the body 35 of the bag in such a manner as to distribute the weight of the bag and its contents evenly throughout the length of both frame-members, this being accomplished by so interconnecting or interlocking the frame-members 40 when in their closed relation that the inner frame-member is supported with relation to the outer frame-member at its ends, and not solely by the lock-mechanism as has heretofore been the practice in this type of 45 bag-frame, this latter practice being objectionable in that it permitted the ends of the inner frame-member to sag away from the outer frame-member, and the whole weight of one side of the bag to be supported merely 50 by the hasps of the lock-mechanism.

Other objects of this invention not at this time more particularly enumerated will be understood from the following detailed description of the present invention.

55 With the various objects of the present

invention in view, the said invention consists, primarily, in the novel bag-frame hereinafter set forth; and, the invention consists, furthermore, in the details of the construction of the parts of said bag-frame 60 more fully described in the following specification, and then finally embodied in the clauses of the claims which are appended to and which form an essential part of this specification. 65

The invention is clearly illustrated in the accompanying drawings, in which:—

Figure 1 is a side elevation of a bag equipped with the novel construction of hingeless bag-frame made according to and 70 embodying the principles of my present invention. Fig. 2 is an end elevation of the same. Fig. 3 is a detail longitudinal section of one end of said bag-frame; and Fig. 4 is a detail cross section of the same taken on 75 line 4—4, looking in the direction of the arrow α , said view being drawn on an enlarged scale.

Referring now to the said drawings, the reference character 1 indicates the complete 80 bag-frame made according to and embodying the principles of my present invention, the same comprising an outer longitudinally extending frame-member consisting of the horizontal body-portion 2 and the downwardly extending vertical flange-portion 3 which projects from the outer-edge of said horizontal body-portion 2, and an inner longitudinally extending frame-member 85 consisting of the horizontal body-portion 4 and the downwardly extending vertical flange-portion 5 which projects from the outer edge of said horizontal body-portion 4. The said inner frame-member is adapted to telescope laterally, or enter, said outer 90 frame-member when the same are associated together in their closed positions or relation one with the other.

The reference characters 6 and 6' indicate the side-sections of the bag-body, and the 100 reference character 7 indicates the end-sections of the bag-body, which are stitched, or otherwise secured to the said side-sections. The upper marginal edge 8 of the side-section 6 of the bag-body is laid against the inner side of said vertical flange-portion 3 of 105 said outer frame-member and an inlay-plate 9 is laid against the same, and then rivets 10, or other suitable fastening devices, are passed through said inlay-plate 9, marginal 110

edge 8 and vertical flange-portion 3 to thereby secure one side-section 6 of the bag-body to said outer frame-member; and the upper marginal edge 8' of the side-section 6' of the bag-body is laid against the inner side of said vertical flange-portion 5 of said inner frame-member and an inlay-plate 11 is laid against the same, and then rivets 12, or other suitable fastening means, are passed through said inlay-plate 11, marginal edge 8' and vertical flange-portion 5 to thereby secure the other side-section 6' of the bag-body to said inner frame-member. The end-sections 7 of said bag-body are provided in their upper parts with a gusseted-portion 13 which folds or collapses together when the bag-frame is closed to shut the mouth of the bag.

The reference character 14 indicates a base-plate upon which is secured the lock-box 15 of a locking-mechanism for locking the respective frame-members in their closed relation. Said base-plate is secured upon the upper surface of said horizontal body-portion 2 of the outer frame-member by means of rivets 16 or any other suitable fastening devices.

The reference character 17 indicates a hasp-plate which is secured to the outer surface of said inner frame-member by means of rivets 18, or any other suitable fastening means, said hasp-plate having hasp-members 19 which enter said lock-box 15 and are engaged by the lock-mechanism contained therein when said bag-frame is closed. Connected with the ends of said base-plate 14 are eye-portions 20 in which are mounted the rings 21 connected with the handle-member 22 of the bag. Also connected with said horizontal body-portion 2 of said outer frame-member, adjacent to the ends thereof, are bearing-members 23 in which are journaled the journal-portions 24 of rotatable holding-members comprising the ears 25 connected with said journal-portions, and which may be turned downwardly to embrace the closed frame-members to prevent their separation from each other at their free end portions. Of course, it will be understood that I may substitute for the lock-mechanism and said holding-members above described any other type of device accomplishing their purposes. The free ends of the horizontal body-portion 2 of said outer frame-member extend outwardly beyond the ends of said vertical flange-portion 3 of said outer frame-member, the same being turned downwardly to form an end-cloisture 26 for said frame-member, and then being further turned inwardly to form a supporting-member 27 in the form of an inwardly extending tongue or lug which lies parallel to and beneath said body-portion 2 of said outer frame-member. The free ends of the horizontal body-portion 4 of said inner frame-member are provided with tongues or lugs

28 which are turned downwardly and thus close the ends of said inner frame-member, and in like manner the free ends of said vertical flange-portion 5 of said inner frame-member are provided with tongues or lugs 29 which are turned inwardly so as to extend across the downwardly turned tongues or lugs 28. The respective tongues or lugs 28 and 29 serve to close the ends of said inner frame-members and at the same time provide an engaging portion which registers over said supporting-member 27 and which engages the same so that the latter may render support to the ends of said inner frame-member when the same is associated in its closed relation with said outer frame-member.

It will be readily understood that when the inner frame-member is telescoped laterally within the outer frame-member in closed relation therewith, that the supporting members 27 of said outer frame-member will engage and support the closed ends of said inner frame-member and thereby prevent the latter from sagging away from its proper association with said outer frame-member or bending or becoming otherwise misshapen, and by this means the weight of the bag and its contents, which is connected with said bag-frame thus constructed, is uniformly and strongly supported from both members of the bag-frame when said members are closed, thus providing all the strength and durability of a hinged bag-frame without the necessity of using such hinged connection of the bag-frame members. It will be apparent therefore that my present invention provides a very cheap but none-the-less efficient and durable bag-frame, more particularly adapted for use in the cheaper grades of hand-bags, satchels and the like.

I am aware that some changes may be made in the arrangements and combinations of the various parts of my novel bag-frame without departing from the scope of my present invention as set forth in the foregoing description, and as defined in the clauses of the claims, which are appended to the said specification. Hence I do not limit my present invention to the exact arrangements and combinations of the various parts as described in the foregoing specification, nor do I confine myself to the exact details of the construction of the said parts as illustrated in the accompanying drawings.

I claim:

1. A bag-frame comprising an outer frame-member and an inner frame-member, the latter being adapted to telescope laterally into the former when said frame-members are closed together, tongues connected with the ends of said outer frame-member the same being bent downwardly and inwardly to provide supporting members

adapted to engage and support the ends of said inner frame-members when said frame-members are closed together.

2. A bag-frame comprising an outer frame-member and an inner frame-member, the latter being adapted to telescope laterally into the former when said frame-members are closed together, tongues connected with the ends of said outer-frame-member the same being bent downwardly and inwardly to provide supporting-members, and means connected with the ends of said inner frame-member adapted to rest in supported engagement with said supporting-members when said frame-members are closed together.

3. A bag-frame comprising an outer frame-member and an inner frame-member, the latter being adapted to telescope laterally into the former when said frame-members are closed together, tongues connected with the ends of said outer frame-member the same being bent downwardly and inwardly to provide supporting members adapted to engage and support the ends of said inner frame-member when said frame-members are closed together, and means for maintaining said frame-members in their closed relation.

4. In a bag-frame an outer frame-member comprising a longitudinally extending horizontal body-portion and a vertical flange-portion extending downwardly from the outer edge of said body-portion, an inner frame-member comprising a longitudinally extending horizontal body-portion and a vertical flange-portion extending downwardly from the outer edge of said body portion, tongues connected with the ends of said body-portion of said outer frame-member the same being bent downwardly and inwardly to provide supporting-members lying parallel to and beneath said body-portion, and tongues connected with the ends of said body-portion of said inner frame-member, the same being bent downwardly to form an engaging portion adapted to rest in supported engagement with said supporting-members when said frame-members are closed together.

5. In a bag-frame an outer frame-member comprising a longitudinally extending horizontal body-portion and a vertical flange-portion extending downwardly from the outer edge of said body-portion, an inner frame-member comprising a longitudinally extending horizontal body-portion and a vertical flange-portion extending downwardly from the outer edge of said body-portion, tongues connected with the ends of said body-portion of said outer frame-member, the same being bent downwardly and inwardly to provide supporting-members lying parallel to and beneath said body-portion, tongues connected with the ends of said

body-portion of said inner frame-member, the same being bent downwardly to form an engaging portion adapted to rest in supported engagement with said supporting-members when said frame-members are closed together, and means for maintaining said frame-members in their closed relation.

6. In a bag-frame an outer frame-member comprising a longitudinally extending horizontal body-portion and a vertical flange-portion extending downwardly from the outer edge of said body-portion, an inner frame-member comprising a longitudinally extending horizontal body-portion and a vertical flange-portion extending downwardly from the outer edge of said body-portion, tongues connected with the ends of said body-portion of said outer frame-member, the same being bent downwardly and inwardly to provide supporting-members lying parallel to and beneath said body-portion, and tongues connected with the ends of said flange-portion of said inner frame-member, the same being bent rearwardly across each end of said inner frame-member to form engaging portions adapted to rest in supported engagement with said supporting-members when said frame-members are closed together.

7. In a bag-frame an outer frame-member comprising a longitudinally extending horizontal body-portion and a vertical flange-portion extending downwardly from the outer edge of said body-portion, an inner frame-member comprising a longitudinally extending horizontal body-portion and a vertical flange-portion extending downwardly from the outer edge of said body-portion, tongues connected with the ends of said body-portion of said outer frame-member, the same being bent downwardly and inwardly to provide supporting-members lying parallel to and beneath said body-portion, and tongues connected with the ends of said flange-portion of said inner frame-member, the same being bent rearwardly across each end of said inner frame-member to form engaging portions adapted to rest in supported engagement with said supporting-members when said frame-members are closed together, and means for maintaining said frame-members in their closed relation.

8. In a bag-frame an outer frame-member comprising a longitudinally extending horizontal body-portion and a vertical flange-portion extending downwardly from the outer edge of said body-portion, an inner frame-member comprising a longitudinally extending horizontal body-portion and a vertical flange-portion extending downwardly from the outer edge of said body-portion, tongues connected with the ends of said body-portion of said outer frame-member, the same being bent downwardly and inwardly to provide supporting-members lying

parallel to and beneath said body-portion, tongues connected with the ends of said body-portion of said inner frame-member, the same being bent downwardly across the 5 end of said inner frame-member, and tongues connected with ends of said flange-portion of said inner frame-member, the same being bent rearwardly across said downwardly bent tongue of said body-portion of said inner frame-member, said respective tongues of said body-portion and said flange-portion of the inner frame-member providing engaging portions adapted to rest in supported engagement with said supporting-members of 10 said outer frame-member when said frame-members are closed together.

9. In a bag-frame an outer frame-member comprising a longitudinally extending horizontal body-portion and a vertical flange-portion extending downwardly from the outer edge of said body-portion, an inner frame-member comprising a longitudinally extending horizontal body-portion and a vertical flange-portion extending downwardly 15 from the outer edge of said body-portion, tongues connected with the ends of said body-portion of said outer frame-member,

the same being bent downwardly and inwardly to provide supporting-members lying parallel to and beneath said body-portion, 30 tongues connected with the ends of said body-portion of said inner frame-member, the same being bent downwardly across the end of said inner frame-member, tongues connected with the ends of said flange-portion of said inner frame-member, the same being bent rearwardly across said downwardly bent tongue of said body-portion of said inner frame-member, said respective tongues of said body-portion and said flange-portion of the inner frame-member providing engaging portions adapted to rest in supported engagement with said supporting-members of said outer frame-member when 35 said frame-members are closed together, and means for maintaining said frame-members in their closed relation.

In testimony, that I claim the invention set forth above I have hereunto set my hand this 17th day of October, 1913.

MORRIS COHEN.
